(57) **CLAIM**

The ornamental design for a license plate box, as shown and described.

DESCRIPTION

FIG. 1 is a perspective view of a license plate box showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof in an opened mode;

FIG. 9 is another front view thereof in the opened mode;

FIG. 10 is another rear view thereof in the opened mode;

FIG. 11 is another left side view thereof in the opened mode;

FIG. 12 is another right side view thereof in the opened mode;

FIG. 13 is another top view thereof in the opened mode;

FIG. 14 is another bottom view thereof in the opened mode; and,

FIG. 15 is an enlarged view of an indicated portion of FIG. 8.

The broken line portions of the license plate box in FIGS. 1-15 represent unclaimed portions of the claimed design and form no part thereof. The dot-dash broken lines in FIGS. 8, 11-12 and 15 represent unclaimed boundary lines and form no part of the claimed design.
